ABSTRACT OF THE DISCLOSURE

Several vehicles connectable together in a train are movable along a roadway. Each carries a sound producing element capable of producing a musical note when struck and a lever that has one end adapted to strike the sound producing element and another end extending below the vehicle. As the vehicle moves along the roadway, the latter end of the lever element hits and rides up over a peg in the roadway. This causes the other end of the lever element to lift up from and then strike down on the sound producing element to produce a musical note. The lever elements on different vehicles are aligned to be actuated by pegs respectively at different positions laterally across the roadway and the pegs are adapted to be placed in the appropriate lateral positions at various points along the length of the roadway for varying the sequence in which the several sound producing elements are actuated as the vehicles move along.

The present invention relates to musical toys and particularly to a music making toy consisting of several vehicles connectable together and movable on a roadway to produce a sequence of musical notes as the train travels along over the roadway.

Musical toys provided by a vehicle, such as a railroad locomotive, adapted to produce musical notes as the vehicle travels along a roadway or track are known. In one known type, tone bars, which produce a musical note when struck, are spaced along the roadway in the manner of railroad ties and the locomotive carries a striker element to strike successive tone bars and produce a succession of musical notes as it travels along the track. A number of tone bars each adapted to produce a different note are provided and they are removably supported under the rails for rearranging them for producing different sequences of the musical notes. It is awkward, however, for a child to have to remove and replace the tone bars in this manner and it detracts from the enjoyment of the toy. Moreover, the number of different sequences of notes which can be set up with this known toy is quite limited.

It is therefore a particular object of the present invention to provide a music making toy which provides simple means for producing a very much larger variety of different combinations and sequences of musical notes than possible with previously known music making toys of the moving vehicle type.

Another object is to provide a toy of this type which is adapted to be constructed in simulation of a railroad train and in which the manner of rearranging the sequence or combination of musical notes does not interfere with, but enhances, a child's imagining he is operating a real train.

In accordance with this invention, the toy consists of several vehicles connectable in a train and movable along a roadway. The vehicles may be made to simulate railroad cars, or any other type of cars movable along a predetermined roadway and each vehicle carries at least one tone bar which is capable of producing a

2

musical note when struck by a striker on the vehicle. An arm of each of the strikers on the several vehicles projects below the respective vehicles at different lateral positions relative to the width of the roadway and pegs for tripping the arms are placed in the roadway to engage the arms and actuate the strikers. The pegs are adapted to be placed in the roadway at intervals along the length of the roadway in lateral positions across the width of the roadway corresponding respectively with the lateral positions of the striker arms. Thus, the sequence in which the strikers are actuated as the vehicles move along the roadway is determined by the positions of the respective pegs along and across the roadway, and the sequence or combination in which the musical notes are produced is varied by rearranging the relative positions of the pegs, and also by rearranging the sequence of the vehicles in the train.

In a preferred form the toy of this invention is embodied in the form of a railroad train, including a locomotive for pulling the vehicles, which simulate railway cars, along the roadway, which is in the form of a railroad track.

Further objects, advantages and features of the toy of this invention will be apparent in the following description of illustrative embodiments shown in the accompanying drawings in which:

FIG. 1 is a side view of a railroad locomotive and railroad cars on a railroad track, embodying a music making toy in accordance with the present invention;

FIG. 2 is a top view of the locomotive, cars and track shown in FIG. 1;

FIG. 3 is a vertical section longitudinally through one of the railroad cars of FIG. 1, illustrating a manner of arranging a tone bar, and striker therefor, on the car;

FIG. 4 is a perspective view, partly in phantom, showing an arrangement of two tone bars, and strikers therefor, on one of the railroad cars of FIG. 1;

FIG. 5 is a view similar to FIG. 3 but showing a modified form of the striker;

FIG. 6 is a perspective view of a section of the track of FIG. 1 showing means for mounting pegs in alternative positions across the track or roadway for actuating the strikers on particular cars;

FIG. 7 is a section along the line 7—7 of FIG. 6;

FIG. 8 is a view similar to FIG. 6 but showing an alternative form of the pegs and means for mounting them across the roadway; and

FIG. 9 is a section along the line 9—9 of FIG. 8.

Referring to the drawings, the illustrative embodiment of a music making toy in accordance with this invention, as shown in FIGURE 1, includes several toy railway cars 10 and a locomotive 11 connected in a train that is movable along a railroad track 12. The track 12 is constituted by parallel rails 14 supported on cross ties 15, and the cars 10 and locomotive 11 are provided with flanged wheels 16 that hold them on the track. While only a straight section of the track 12 is illustrated, it will be appreciated that the track may be made any desired length and be arranged in any desired configuration; it is preferably arranged to form a continuous circuit.

The cars 10 and locomotive 11 are suitably coupled together in a flexible and readily detachable manner by simple pin and hole couplings 17 which enable the cars to be connected in any sequence. As shown the couplings 17 are each provided by a plate 18 extending from the rear end of the locomotive and from one end of each car 10 and having a hole therein to receive a pin 19 projecting down from the underside of a tongue 20 that is pivotally attached to the other end of each of the cars. The locomotive 11 may be hand pushed or self-propelled, by a conventional wind-up motor or electric motor, for example.

Each of the cars 10 carries at least one tone bar 22, which produces a musical note when struck and a striking lever 23 that is adapted to be tripped by a peg 24 on the track 12 and strike the tone bar for producing its musical note as the car is moved relatively past the peg 24. The several cars 10 are each preferably provided with a tone bar 22 for producing a different musical note or tone and two or more tone bars may be mounted on each car. In its preferred form, the toy includes at least one tone bar for each note on the music scale; these may be provided on a separate car for each tone bar and/or by two or more of the tone bars on each of several cars. The portions of the striking levers that are engaged by the respective pegs for tripping the levers associated respectively with the different tone bars, and the pegs engaged thereby, are each in a different position relatively across the width of the track. Thus, the positions of the respective pegs across the track and their relative positions along the length of the track determine the sequence in which the tone bars are struck.

Suitable structure of the tone bars 22 and striking levers 23, and their arrangement on the cars 10 are illustrated by the car 10 depicted in FIG. 3, wherein a tone bar 22 rests across two spaced resilient supports 26 on the floor of the car 10 and is held in position thereon by pegs 27 projecting loosely up through appropriate holes in the tone bar; the latter holes are made large enough for the tone bar to be lifted off for switching the tone bars around between different cars, or otherwise replacing the tone bar with a different one. The striker lever 23 is an L-shaped lever formed by arms 28 and 29 attached to a cross bar 30 and extending therefrom approximately at right angles to each other. The cross bar 30, which has upturned ends 31, is pivotally supported between the side walls of the car 10 by a rod 32 received through the ends 31, with the ends of the rod 32 being journaled in opposite walls of the car. The arm 28 has a striker head 34—shown as a ball—normally resting on the tone bar 22 and the arm 29 extends down through an opening in the floor of car 10 so that its lower end 29a is down far enough to engage a peg 24 that is on the track 12 in line to be engaged by the end 29a. As the car moves in the direction of arrow 35, the lower end 29a of the lever engages a peg 24; the lever then swings back and up to the position indicated in dash-line as the lower end 29a to ride up and over the top of the peg. The lever swings down and back again by its own weight after the end 29a is carried past the peg, so that the striker head is thus lifted up from and then dropped down on the tone bar 22 to produce a musical note. As shown, the front and rear end portions of the cars 10 have solid walls 36 and the middle portions have open frames, indicated at 37, for letting the sound of the tone bar out. For the same purpose, openings 38 may be provided in the floors of the cars.

The striking force of the striker head 34 may be increased by inserting a spring 40 between the top side of the arm 28 and the top of a car 10, but the spring is not essential.

FIG. 4 shows a car 10a having two of the tone bars 22, and striking levers 23 therefor, and illustrates the manner in which striking levers 23 are arranged in different positions relative to the widths of the cars in order for their lower ends 29a to be engaged by pegs 24 arranged respectively in different lateral positions across the track 12.

FIG. 5 shows a car 10b in which the striker lever 28 is constructed to be operated by movement of the car 10b in reverse of the direction indicated for the operative movement of the car 10 of FIG. 3. With the car 10b the striker lever 28 is tripped by a peg 24 on the track when the car moves in the direction of the arrow. For this purpose, a lever arm 39, formed in two parts 39a and 39b flexibly connected together, is substituted for the arm 29 of the lever striker 28 of FIG. 3. As shown in FIG. 5, the part 39b is a short stub attached to the cross bar 30

5 of the lever and the lower part 39a, which has its lower end extending below the floor of the car 10b to be engaged by a peg 24, is mounted to swing on a rod 42, which passes through the part 39a at a point near, but below, the upper end of the part, and which is appropriately supported between opposite walls of the car. The upper end of the part 39a is linked to the part 39b by a pin 43 projecting from the side of part 39b and received in a vertical groove 44 in the part 39a. Thus, as the car 10b moves to the right in the direction of arrow 41, the lower end of part 39a engaging a peg 24 on the track causes the striking lever 23 to be swung to the dash-line position indicated and back again to strike striker head 34 on the tone bar 22.

10 In a preferred form of the invention, eight tone bars 22, each capable of producing a different one of the eight tones or notes of the musical scale, are provided on the cars 10. These tone bars may each be carried on a separate car, or two or more may be placed on one car in the manner shown in FIG. 4. In either case, the arms 29 of the striking levers 23 for the respective tone bars are each arranged to project below the respective cars at a different position relative to the width of the track 12 so that the several arms 29 are tripped respectively by pegs 24 in comparable positions across the width of the track. Therefore the pegs 24 are adapted to be positioned alternatively in any one of eight positions across the width of the track—each position representing a tone or note on the musical scale—and provision is made for thus positioning pegs 24 at regular intervals along the length of the track. This latter interval, in conjunction with the speed at which the cars 10 are moved along the track, determines the time between the sounding of one note on the musical scale—and provision is made for explained below.

15 FIGS. 6 to 9 illustrate two different suitable means for supporting and positioning pegs 24 in alternative positions on a roadway—the track 12 in this instance. In the form shown in FIGS. 6 and 7, the pegs 24 each have a stud 46 projecting from the bottom to be received in any one of eight holes or wells 47 that are in the upper surface of each cross tie 15 in a row across the width of the track between the rails 14. Each hole 47 represents a musical note and a number of pegs 24 amounting to the total number of notes are placed in selected holes 47 20 in selected cross ties 15 to produce the desired sequence of notes as the several vehicles 10 move along the track. In effect, the pegs 24 are positioned in selected holes 47 for producing a sequence of musical notes just as symbols for musical notes are placed in certain positions on a musical staff to indicate the particular notes to be sounded and the sequence of sounding them.

25 Another suitable arrangement for placing pegs in selected positions along the track 12 is illustrated in FIGS. 8 and 9. In this arrangement, pegs 24a, which are flat on the bottom, are arranged in a group of eight across each cross tie 15 and are individually hinged, by hinges 49 on the respective ties. As shown in FIG. 9, each peg 24a is hinged to an edge of the respective tie 15 to be upright on the tie in line to engage an arm 29 of a striker lever 28 on a car moving in the direction of arrow 50, or to be tripped over and swung down to a position, shown in dash-line, in which the arm 29 of a striking lever will pass over it without being tripped. Thus, selected pegs 24a are set in their upright positions to establish which tone bars 22 will be struck, and in what order, as the cars 10 move along the track; the other pegs 24a will, of course, be swung down to the sides of the ties to be out of the way.

30 FIG. 2 illustrates the manner in which pegs 24 and cars 10 are arranged for the tone bars 22 on the several cars to be sounded in a predetermined sequence. In this figure the cross ties 15 along part of the track 12 are designated 15a 15b, 15c and 15d in sequence from the top down; a train of cars pulled up the track 12 by the locomotive 11 are designated 110, 110a and 110b, and

the striker lever arms that are tripped by pegs 24 for sounding the tone bars on the respective cars are indicated schematically by short lines designated 129, 129a, 129b and 129c. As indicated, the arm 129 on car 110 is in line to be tripped by a peg 24 in the second hole 47 from the left in tie 15c, the arm 129a on car 110a is in line with a peg 24 in the fourth hole from the left in tie 15a, and the arms 129b and c on car 110b are in line respectively with a peg 24 in the third hole from the left in tie 15d and a peg 24 in the seventh hole from the left in tie 15b.

In FIG. 2 the ties 15 and 15a to d, are shown spaced so that the distance between each three ties is the same as the distance between the lower arms (arms 129 and 129a, for example) of the striker levers on each two successive cars. This spacing, however, is illustrative only; it is not critical, and is a matter of choice.

With the spacing of the ties and arrangement of pegs 24 and cars 110 to 110b shown in FIG. 2, it will be seen that the sequence in which the arms 129 to 129c will be actuated by the respective pegs 24 to sound the tone bars 22 as the train moves up the track is, first, arm 129 (by peg 24 on tie 15c), arm 129b by peg 24 on tie 15d), arm 129a (by peg 24 on tie 15a) and then arm 129c (by peg 24 on tie 15b).

It will then be seen that the sequence in which the tone bars 22 are sounded is determined both by the arrangement of the pegs 24 in the several possible positions across the ties 22 and the sequences in which the several cars 10 are connected in a train, and that the time interval between the soundings of the time bars produced by pegs on successive ties 15 is determined both by the spacing of the ties and the speed at which the train is moved along the track. Thus, the toy of this invention is capable of being used to produce a fascinating and almost infinite variety of combinations and sequences of musical notes.

What is claimed is:

1. A music making toy comprising several vehicles connectable in a train and movable along a roadway, each of said vehicles carrying a sound producing element capable of producing a musical note when struck and striking means for striking said element, and trip means on the roadway for actuating the said striking means as the vehicles move past them, the striking means on different vehicles being arranged for each to be actuated by a different one of said trip means and each different trip means being in a different lateral position relative to the width of the roadway, and means for locating said trip means in alternative actuating positions laterally across the roadway at intervals along the length of the roadway, for arranging the trip means to produce musical notes in a desired sequence when the train is moved along said roadway.

2. The toy of claim 1 including a self-propelled power vehicle adapted to ride on said roadway and being connectable to one of the other of said vehicles for moving a said train of the latter vehicles along the roadway.

3. The toy of claim 1 including a vehicle having thereon more than one of said sound producing elements and one of said striking means for each of the said sound producing elements, the latter striking means each being arranged to be actuated by a different one of said trip means and each different trip means being in a different lateral position relative to the width of said roadway.

4. The toy of claim 1 in which said trip means comprise pegs adapted to be received and supported in holes in portions of said roadway, said holes being arranged in rows laterally across said roadway with said rows being

spaced apart at intervals along the length of said roadway.

5. The toy of claim 1 in which said trip means comprise a plurality of pegs arranged in rows laterally across said roadway, each of said pegs being hinged to a portion of said roadway to be adapted to swing from a first position, in which its free end is in line to actuate the striking means on one of said vehicles moving along the roadway, to a second position, in which its free end is out of said line, whereby a sequence of musical notes to be produced is selected by swinging some of said pegs to said first position and the others to said second position.

6. The toy of claim 1 in which said sound producing elements respectively on each of several of said vehicles are each adapted to produce a different musical note and in which said vehicles are adapted to be connectable together in alternative sequences.

7. The toy of claim 1 in which said striking means comprises an L shaped lever having first and second arms joined at an elbow, said elbow being pivotally mounted on said vehicle for a striker element on said first arm normally to rest on said sound producing element and for the outer end of said second arm to be in position to engage one of said trip means on the roadway as said vehicle is moved to said one trip means, said outer end of the second arm and said trip means being located for said outer end to be swung back and upward by said one trip means and to pass over it and swing down and forward again as said vehicle moves relatively past the said one trip means in one direction, thereby to swing said first arm, and said striker element thereon, up from and then drop it down again for producing a musical note.

8. The toy of claim 7 in which said second arm of said lever is in two parts, the upper part being joined at said elbow to said first arm and the lower part being pivotally mounted below the upper part to swing in the same plane as the upper part, the upper end of said lower part and the lower end of said upper part being operatively connected by a pin projecting from a side of one of the parts and received in a generally vertical slot through the other of said parts, whereby pivotal movement of the lower part in one direction swings the upper part, and said first arm joined thereto, in the opposite direction.

9. The toy of claim 7 in which said roadway is a railroad track comprising parallel rails supported on cross ties and said vehicles are adapted to move along on said rails, and which includes a locomotive adapted to ride on, and be moved along on, said rails and being connectable to one of said vehicles for pulling a train of said vehicles along said track, said trip means being pegs adapted to project up from said cross ties in position to engage the said second arms of respective striking means on said vehicle for actuating said striking means as said vehicles move along the track.

10. The toy of claim 9 in which said locomotive is self-propelled.
